FREQUENCY MODULATOR WITH BLOCKING OSCILLATOR

William H. Swain, Sarasota, Fla., assignor to Electro-Mechanical Research, Inc., Sarasota, Fla., a corporation of Connecticut

Filed Aug. 25, 1960, Ser. No. 51,938
2 Claims. (Cl. 332—16)

This invention relates to variable frequency signal generators and, more particularly, to such generators whose frequency is linearly varied by incoming intelligence signals.

In the rapidly developing art of telemetering systems associated with guided missiles, pilotless aircraft or projectiles, for example, automatic measurement instruments are provided for recording changing physical, electrical and magnetic phenomena. In such systems, means are usually provided for converting the variable phenomena into corresponding electrical intelligence signals. These signals are then used to linearly modulate the frequency of a local sub-carrier oscillator. The frequency modulated signals from a plurality of such sub-carrier oscillators are then fed to a main carrier modulator network of a radio transmitter energizing an outside antenna.

Receiver means at a remote point, either on ground or elsewhere, pick up the transmitted frequency modulated composite carrier wave and convert it into a main sub-carrier signal from which the component F-M modulated sub-carrier signals are filtered out. Finally, frequency discriminator circuits extract from the F-M sub-carrier signal the input intelligence signal.

Although various voltage controlled oscillators (hereinafter referred to as VCO) are already known in the art, they possess certain inherent disadvantages which prevent their use in the latest subminiaturized equipments, operating under severe environmental conditions.

Accordingly, my invention is primarily concerned with the provision of a VCO which uses a minimum number of components which can be housed in a very small volume, which is especially suitable for printed circuit techniques and which consumes very little power. This is accomplished by utilizing miniature components some of which perform several functions during a single period of operation of the sub-carrier oscillator.

It is therefore an object of the present invention to provide new and improved subminiature frequency modulation systems which are very stable and whose frequency deviation is linearly proportional over a wide range of the magnitude of the randomly incoming modulating signals.

Another object of my invention is to provide systems of the foregoing character in which extremely small incoming modulating signals produce wide frequency deviations.

A further object of this invention is to provide such frequency modulation systems which are essentially insensitive, over a wide operating range, to changes in environmental conditions such as temperature, pressure, shock and vibration, and to acoustic or electric field noise.

Yet a still further object of this invention is to provide a modulation system having a linear frequency deviation response to D-C. as well as to rapidly changing intelligence signals.

Another object of this invention is to provide in systems of the foregoing character a stable periodic pulse generator, the interpulse period of which may be shifted by a small voltage or current.

Further objects and advantages of my invention will become apparent as the following description proceeds and the features of novelty which characterize my invention will be pointed out with particularity in the claims annexed to and forming part of this invention.

2

In accordance with this invention, an oscillator or periodic pulse generator is coupled to a modulator circuit for deviating the frequency of oscillation of the oscillator or the pulse repetition rate of the pulse generator. If it is desired to have a sub-carrier sine wave, the pulses, after being amplified, may be applied to a special band pass filter. The preferred embodiment of my invention utilizes a transistorized blocking oscillator having a parallel resistor-capacitor timing network and a pulse transformer with a plurality of inductively coupled windings mounted on a small high permeability core. The modulating network includes a transistorized chopper. The intelligence signals are applied directly to the chopper or through an integrating network.

The charge on the timing capacitor may be dissipated through the timing resistor without flowing to ground or through any intelligence receiving input circuits, thereby making the oscillator (or periodic pulse generator) appear as a passive impedance load to the input circuit. Thus, the oscillator or pulse generator becomes isolated from the signal source and does not feedback thereto any voltage or current.

The feedback winding of the precision blocking oscillator is connected to the output terminal of the chopper, the time operation of which is determined by a control winding. While the modulating signals bias the R-C timing circuit only during the relaxation period of each cycle thereby determining the interpulse repetition frequency, they are solidly chopped to ground during the main pulse of the oscillator. If desired, the main pulse of the blocking oscillator after being amplified, may be applied to a band pass filter thereby producing a sine wave whose frequency corresponds to the interpulse repetition frequency.

The invention will be better understood from the following detailed description taken in conjunction with the accompanying drawings in which:

FIG. 1 is a schematic diagram of a frequency modulation system in accordance with my invention; and

FIGS. 2A, 2B, 2C and 2D show four voltage wave forms as a function of time at critical points of the modulation system.

In FIG. 1 is shown a frequency modulation system comprising a first transistor Q_1 in the tunable blocking oscillator circuit, a second transistor Q_2 in the chopper circuit and a third transistor Q_3 in the pulse amplifying circuit. These transistors are of the PNP type, although the NPN type transistors could also be utilized, as is known in the art. The emitter of Q_1 is connected to the positive terminal B of the energizing voltage V_B . The base of Q_1 is connected to ground through the parallel C_3R_4 precision timing circuit, feedback winding N_6 and emitter-collector circuit of Q_2 . The collector of Q_1 is connected to ground through the main pulse output winding N_5 . The base of Q_2 is connected to ground through current limiting resistor R_{11} , chopper control winding N_7 and parallel $R_{10}C_9$ biasing circuit. The signal input terminals I, I' are connected to the integrating or low pass filter network R_1C_2 , as shown. Terminal B is connected through main pulse transfer winding N_8 , base collector circuit of Q_3 to the input terminal Q of the band pass filter comprising inductors L_A , L_C , L_E and capacitors C_B , C_D and C_F connected as shown. The emitter of Q_3 is directly connected to terminal B and through filter capacitor C_{11} to grounded terminal B'.

The four windings of the pulse transformer are wound on a small high permeability core which may be of ferrite in directions illustrated by the conventional dots. The output F-M modulated sine wave is derived from terminals O, O' across output load R_0 , while the modulating signals V_m are applied to input terminals I, I', terminal I' being grounded, as shown.

The four windings of the pulse transformer are wound on a small high permeability core which may be of ferrite in directions illustrated by the conventional dots. The output F-M modulated sine wave is derived from terminals O, O' across output load R_0 , while the modulating signals V_m are applied to input terminals I, I', terminal I' being grounded, as shown.

In FIG. 2 are shown in cartesian coordinates four voltage wave forms as a function of time. FIG. 2A is the integrated modulating signal at the emitter junction of Q_2 ; FIG. 2B is the voltage wave form at the base of the blocking oscillator transistor Q_1 ; FIG. 2C is the oscillator output pulse at the collector of Q_1 ; and FIG. 2D shows the output sine wave across terminals O, O' .

A detailed description of the voltage controlled oscillator of the present invention will now be given. Since the mathematical analysis of the system is complex, the transistor action herein will be idealized and certain assumptions made which will lead to approximate equations relating the parameters which determine the critical variables of the circuit.

The analysis will be aided by considering the shape of the waveforms at the critical times thereof.

First, at t_{0+} transistor Q_1 becomes quickly saturated due to the regenerated effect between windings N_5 and N_6 , as is well known in the art of blocking oscillators. Therefore, Q_1 acts as a closed switch making its collector-emitter voltage approach zero, its collector voltage v_c then reaches rapidly the energizing value V_B , and its collector current begins to increase toward a maximum. The current in the collector of Q_1 develops a positive voltage pulse:

$$(e = L \frac{di_1}{dt})$$

in winding N_5 . Hence, at t_{0+} , v_c (of Q_1) = V_B , as shown in FIG. 2c. This positive pulse in turn produces a negative going voltage pulse in windings N_6 and N_7 .

The negative pulse in N_7 saturates chopper transistor Q_2 , thereby making its emitter-collector voltage approach zero and allowing its base to draw a maximum current which charges biasing capacitor C_9 through current limiting resistor R_{11} .

Since the dotted terminal of winding N_6 becomes virtually grounded through the emitter-collector of chopper Q_2 at t_{0+} , the negative going pulse in winding N_6 will appear at the base of transistor Q_1 because the voltage across timing capacitor C_3 cannot change instantaneously. At t_{0+} , Δv_b (of Q_1) = $(i_{b1})(r_{b1})$, where i_{b1} is the base current and r_{b1} is the non-linear base resistance. Thereafter, C_3 will charge to the supply voltage V_B plus the voltage $V_B(N_6/N_5)$ appearing across winding N_6 , where N_6/N_5 is the turns ratio between windings N_6 and N_5 .

To summarize, at t_{0+} , voltage V_B is across winding N_5 , a negative pulse appears at the base of Q_1 , and the emitter of chopper transistor Q_2 is grounded. Timing capacitor C_3 charges during period T_1 which ends at $t=T_b$ when the collector of Q_1 can no longer supply the current needed in winding N_5 in order to provide for all the required currents flowing out of the base of transistor Q_1 and the base of transistor Q_2 , and for the continuously increasing core magnetizing current. Since the inductors on the ferrite core are linear, the current in N_5 during the main pulse interval T_1 increases approximately linearly with time.

For example, if the inductance L_5 of winding N_5 is such that the peak current in N_5 is about 7 milliamps; if T_1 is at 5 to 10% of T_0 where T_0 is equal to $1/F_0$ and F_0 is the operating center frequency of the oscillator in the absence of an input modulating voltage, and if the effective value of the non-linear base resistance r_{b1} of transistor Q_1 is approximately equal to 1,000 ohms, then the period T_1 is given by the following approximate equation:

$$T_1 = (r_{b1})(C_3) \quad (1)$$

At the end of period T_1 , i.e., at $t=T_b$, the current flowing through N_5 decreases since Q_1 can no longer supply the demand of N_5 , and due to the regenerative action of the other windings, the collector voltage v_c of Q_1 falls rapidly below ground potential to a value V_D , where V_D is a base-emitter voltage drop, thereby cutting off transistor Q_1 . Simultaneously, the negative going pulse in winding N_5 produces positive going pulses in windings N_6 and N_7 .

The positive pulse in winding N_7 cuts off chopper transistor Q_2 which is equivalent to opening a switch across capacitor C_2 . The positive going pulse in winding N_6 appears at the base of transistor Q_1 , since again the voltage across C_3 cannot change instantaneously. Therefore, at $t=T_b$:

$$v_b \text{ (of } Q_1) = V_B (1 + N_6/N_5)$$

One important criterion for T_1 is that it be long enough to permit the timing condenser C_3 to be fully charged, that is, to reach a voltage equal to $V_B - V_D$ plus the voltage across N_6 where V_D is the base-emitter voltage drop of Q_1 . V_D is similar to the voltage drop across a diode in the forward direction. Were T_1 not long enough to satisfy this condition, the cut-off period T_u of the oscillator would still be determined by the amount of charge on C_3 , as well as by all the other usual parameters. This condition would deteriorate the temperature stability of the modulation system.

Following the main pulse period T_1 of the blocking oscillator Q_1 , the current in Q_1 collapses with regenerated speed. Energy stored in the core of the pulse transformer causes the voltages across the transformer windings to reverse thereby making winding N_8 to act as a virtual battery for a period T_2 . During this period the voltage induced in winding N_8 forward biases the base emitter junction of Q_3 thereby causing it to draw collector current. Period T_2 ends when the entire energy from the core of the transformer is dissipated in the base-emitter junction of Q_3 across N_8 , and in various losses.

Period T_2 can be modified by altering the turns ratio N_8/N_5 , and/or by shunting an energy release diode across one or several windings, and/or by connecting across one or several windings a damping resistor. The remaining period T_3 of the relaxation period T_u terminates at $t=T_a$ when the voltage across timing condenser C_3 discharges to a point low enough to cause the base of Q_1 to again draw forward current. Therefore, the next main pulse of the blocking oscillator occurs at the end of the relaxation period T_u when the base voltage of Q_1 equals the emitter voltage V_B minus the emitter-base voltage drop V_D . In accordance with this invention, the relaxation time period T_u primarily depends on the time constant of the timing circuit C_3R_4 , and the effective modulating voltage v_i across capacitor C_2 . T_u depends only secondarily upon the main blocking oscillator period T_1 . It can be shown that T_u is approximately given by:

$$T_u = R_4 C_3 L_n \left\{ \frac{1 + N_6}{1 - x} \right\} \quad (2)$$

where:

$$x = v_i/V_B \quad (v_i \text{ taken at the end of } T_u),$$

N_6/N_5 is the turns ratio between windings N_6 and N_5 ,

L_n is the natural logarithm,

and

x is called the direct input modulation factor.

The center frequency F_0 is obtained by making the input voltage and, hence, x equal to zero in Equation 2. Therefore:

$$T_0 = 1/F_0 = T_1 + T_u(v_i=0) = T_1 + R_4 C_3 L_n (1 + N_6/N_5) \quad (3)$$

and the repetition period T between the main pulses of the blocking oscillator is:

$$T = T_1 + T_u \quad (4)$$

The modulating signal voltage V_m is applied to the integrating or low pass filter network R_1C_2 . As was seen previously, from t_{0+} to $t=T_b$, the effective modulating voltage v_i across C_2 is near ground potential due to the conduction of Q_2 . At $t=T_b$, the positive pulse in winding N_7 cuts off transistor Q_2 , thereby opening the switch

across integration capacitor C_2 . Since the time period T of one cycle of the blocking oscillator is generally, but not necessarily, very short compared to one period of the modulating intelligence signal, it will be hereinafter assumed that the modulating voltage V_m remains constant over the relaxation period T_u . It should be noted that this is only a convenient assumption and is not intended to be a restriction.

Modulating voltage V_m charges condenser C_2 through R_1 up to the end of period T_u to an asymptotic value equal to V_m , as shown in FIG. 2A. The timing network of the blocking oscillator C_3R_4 sitting directly on the integrated modulating signal has its discharge time determined in part by the integrated voltage on C_2 attained at the end of the relaxation period T_u .

In summary, chopper transistor Q_2 is closed (conducting) during T_1 by the voltage induced in winding N_7 and Q_2 is open (cut-off) during relaxation period T_u because its base-emitter junction is reverse-biased by the voltage developed during T_1 on the parallel C_9R_{10} network by its base current. The base resistor R_{11} limits the peak base current of Q_2 during T_1 .

Let $u = V_m/V_B$ where u is defined as the modulation input voltage factor; then it can be mathematically shown that the interpulse period T is approximately equal to:

$$T = \frac{1}{F} = r_{b1}C_3 + R_4C_3L_n \left\{ \frac{1 + \frac{N_6}{N_5}}{1 - u \left[1 - \frac{e^{-T_u}}{R_1C_2} \right]} \right\} \quad (5)$$

It has been experimentally found that practical oscillators perform close to this relation when corrected for the transistor base emitter voltage drop V_D .

Examining the analysis of Equation 5 and the experimental data obtained from several oscillators, it appears that the frequency F can be made a linear function of the input voltage V_m for deviations up to $\pm 7.5\%$ with a maximum departure from the best straight line (BSL) of $\pm 0.05\%$. The linearity for $\pm 15\%$ deviation of F can be held to $\pm 0.1\%$ BSL. The sensitivity of the circuit is excellent. It was found that a five volt signal V_m causes well over $\pm 7.5\%$ deviation when the ratio N_6/N_5 is equal to one-half. In order to limit the sensitivity of the voltage controlled oscillator, a shunting resistor may be connected across integrating capacitor C_2 .

The sine wave output signal is obtained across output terminals O, O' of the band pass filter. Energy is stored in the core of the pulse transformer during the main pulse period T_1 and is released to the base emitter junction of the output pulse transistor amplifier Q_3 during the interval T_2 . The amplified output of Q_3 functions as a time variable current source driving the band pass output filter.

The band pass filter is typically terminated in a 5,000 ohm load R_0 either internal or external to the voltage controlled oscillator. It produces a pure sub-carrier sine wave, as shown in FIG. 2D, whose frequency corresponds to the interpulse frequency of the blocking oscillator. The available sine wave output voltage across terminals O, O' is three to five volts R.M.S. with less than 1% sub-carrier distortion at any point in the designed channel when the system operates from a nine volt power source V_B with a 40 milliwatt drain. Intelligence signals deviating the sub-carrier sine wave by $\pm 7.5\%$ of center frequency at the rate corresponding to a modulation index of 5 are distorted less than 1% as a consequence of the wide pass band and linear phase characteristics of the filter. The amplitude of the sub-carrier level changes less than ± 1 db across the designed channel.

The output circuit is so completely isolated from the frequency determining section that the mixing of the output signals from a number of oscillators may be accomplished in simple resistors to drive a sub-carrier multiplex line, transmitter or recorder, etc. Since the output level of each VCO is three to five volts R.M.S. and the total load is 5,000 ohms, this summing line can

generally provide about 1.0 volt R.M.S. sub-carrier multiplex signals at a source impedance of 1,000 ohms or less.

When the elements of the filter are arranged as shown in FIG. 1 and are such that the characteristic impedance of the L, C sections increases as one progresses from $L_A C_B$ through $L_e C_D$ to $L_e C_f$ toward the output load, then the low impedance time variable source Q_3 appears essentially under pulse operations as a current source thereby eliminating the need for matching resistors which would reduce the overall power efficiency and increase the weight of the subminiature VCO. This is an especially useful property for the circuit in accordance with my invention, since the input of the filter can be driven directly from a switch type transistor such as Q_3 . The resulting output wave has a relatively high voltage level even at low impedance with good power supply efficiency (15% or better in some cases). For example, when $F_0=5030$ c.p.s. and $R_0=3170$ ohms, the values for the L's and C's should be approximately selected as follows:

$$\begin{aligned} L_A &= 4.1 \text{ milli-henries} \\ C_B &= .29 \text{ micro-farad} \\ L_e &= 24 \text{ milli-henries} \\ C_D &= .0465 \text{ micro-farad} \\ L_e &= 74.7 \text{ milli-henries} \\ C_F &= .011 \text{ micro-farad} \end{aligned}$$

The voltage controlled oscillator, in accordance with this invention, is particularly suitable for the transmission of pulses rich in harmonic content. Since the pulse response of the circuit is sufficiently damped, it does not appreciably ring or overshoot. It was found that the rise time is about 0.6 the total period of one sub-carrier cycle for a VCO operating at $\pm 15\%$ deviation.

The choice of circuit elements employed in the system in FIG. 1 is subject to wide variation. Merely to exemplify the practice of the invention and not in restriction of its scope, the following set of values is given for some of the frequency determining components.

Transistors Q_1 , Q_2 and Q_3	Philco type 2N495 or 2N496.
R_1 , R_4 , R_{11} and R_{10}	470k, 33k, 1k and 5k, respectively.
C_{11} and C_9	1.0 micro-farad.
V_B	9 volts.
r_{b1}	1,000 ohms.
N_8/N_5	1 (one).
V_B/V_D and T_2/T_1	8.
N_6/N_5 and N_7/N_5	One-half.
R_4C_3/R_1C_2	Generally between 1 and 2.

In summary, certain salient features of the circuit of this invention will be outlined infra.

It was found that even though Equation 5 in column 5 is apparently a non-linear function, the frequency deviation (or pulse period deviation) can be made a linear function of an input voltage or current over a wide range ($\pm 15\%$ of basic period) by suitably selecting time constants R_1C_2 and R_4C_3 .

Also, the use of linear inductors in the pulse transformer and in the filter to alternately store and release energy produces a substantial output power with better power supply efficiency than that obtainable in the prior art systems of this character.

This is in part due to the concept of storing energy in the core of the pulse transformer during interval T_1 at a relatively high voltage, and releasing it over a relatively long period T_2 at a lower voltage.

The excellent isolation between the output load (including the band pass filter) and the precision time or frequency determining element is obtained, in accordance with this invention, by disconnecting the output load during T_1 from the components producing the main pulse. The load is driven only during period T_2 (the base emitter junction of Q_3 is biased off during T_1) when the pulse circuitry is not required to perform a precise time func-

tion. Thus, excellent isolation is obtained on a time sharing basis with a minimum number of components.

The circuit is also well isolated from the input load across terminals I,I'. A change in input impedance from short to open circuit causes less than $\pm 2\%$ in output frequency.

The invention is susceptible to certain modifications which will readily suggest themselves to the man skilled in the art.

For example, to make T a linear function of V_m the integrating network R_1C_2 may be replaced by a network which would transform the incoming intelligence signals V_m into an input modulating voltage v_1 as a function of V_m capable of biasing the return voltage of N_6 during T_u . This network should preferably have an impedance, just prior to the decision instant when $t=T_a$ in FIG. 2B, in the order of 1,000 ohms or less at a frequency of about 30 times greater than the pulse repetition frequency.

Also an alternative relaxation oscillator may be used with the same input configuration consisting primarily of C_3R_4 , N_6 , Q_2 and R_1C_2 . Also, for some applications it is often desirable to make T_1 approximately equal to T_u , i.e., to obtain a square wave oscillator. This may be readily accomplished by a mere change in the value of the components shown in FIG. 1.

Other components which may be added in order to linearize the frequency or interpulse period deviation function of the VCO include an inductor in series with R_1 and/or an RC time constant inserted in series with the emitter or Q_1 .

It should be understood that the output signal need not be taken from terminals O,O'. The circuit may be made to function as a pulse generator with a linearity variable interpulse period by deriving the output from terminals P,P' across N_3 (Q_3 and the filter being omitted), or from terminals Q,Q' (the filter being omitted).

The circuit as shown in FIG. 1 can be housed in a box not bigger than 3.4 cubic inches. The weight of the entirely assembled VCO can be made less than 5 ounces. The unit is extremely reliable from -55° C. to $+125^\circ$ C. A change in center frequency of less than 3% from its corresponding value at $+25^\circ$ C. results over a temperature range of -25° C. to $+100^\circ$ C.; the bandwidth being stable within 3% over the same temperature range.

Vibration in three mutually perpendicular planes at 20 g. acceleration up to a frequency of 2,000 c.p.s. results in a frequency variation of less than 1% of full bandwidth.

The unit is also very stable at high altitude: a change from three atmospheres to 100,000 feet produces less than $\pm 1\%$ variation in center frequency and bandwidth. The VCO is also unaffected by relative humidity of up to 100% when a hermetic box is employed.

Although this invention has been described with respect to preferred specific embodiments thereof, it is not

to be so limited since changes and modifications may be made therein which are within the full intended scope of this invention, as defined by the appended claims.

What is claimed is:

- 5 1. A frequency modulator comprising a blocking oscillator, a parallel resistance-capacitance timing network for determining the length of the periodically alternating "on" periods and "off" periods of said oscillator, a main winding in the output circuit of said oscillator, a feedback winding coupled to said main winding and connected to said timing network, a control winding coupled to said main winding, a source of modulating signals, integrating means for integrating said modulating signals, and chopper means being connected in parallel with said integrating means and being energized by said control winding for transferring said signals from said source to said feedback winding during said "off" periods and for short circuiting said integrating means during said "on" periods.
- 10 2. A frequency modulator comprising a blocking oscillator, said oscillator including a semi-conductor device having an emitter, a base and a collector; a pulse transformer having a main winding, a feedback winding and a control winding mounted on a high permeability core, said main winding being connected to said collector; a parallel resistance-capacitance timing network connected between said feedback winding and said base, a source of input intelligence signals, an integrator for integrating said intelligence signals, a semi-conductor chopper having an emitter, a base and a collector; means for connecting said emitter and said collector of said chopper across said integrator, and means for connecting said control winding to said base of said chopper.
- 15 3. A frequency modulator comprising a blocking oscillator, said oscillator including a semi-conductor device having an emitter, a base and a collector; a pulse transformer having a main winding, a feedback winding and a control winding mounted on a high permeability core, said main winding being connected to said collector; a parallel resistance-capacitance timing network connected between said feedback winding and said base, a source of input intelligence signals, an integrator for integrating said intelligence signals, a semi-conductor chopper having an emitter, a base and a collector; means for connecting said emitter and said collector of said chopper across said integrator, and means for connecting said control winding to said base of said chopper.
- 20 4. A frequency modulator comprising a blocking oscillator, said oscillator including a semi-conductor device having an emitter, a base and a collector; a pulse transformer having a main winding, a feedback winding and a control winding mounted on a high permeability core, said main winding being connected to said collector; a parallel resistance-capacitance timing network connected between said feedback winding and said base, a source of input intelligence signals, an integrator for integrating said intelligence signals, a semi-conductor chopper having an emitter, a base and a collector; means for connecting said emitter and said collector of said chopper across said integrator, and means for connecting said control winding to said base of said chopper.
- 25 5. A frequency modulator comprising a blocking oscillator, said oscillator including a semi-conductor device having an emitter, a base and a collector; a pulse transformer having a main winding, a feedback winding and a control winding mounted on a high permeability core, said main winding being connected to said collector; a parallel resistance-capacitance timing network connected between said feedback winding and said base, a source of input intelligence signals, an integrator for integrating said intelligence signals, a semi-conductor chopper having an emitter, a base and a collector; means for connecting said emitter and said collector of said chopper across said integrator, and means for connecting said control winding to said base of said chopper.
- 30 6. A frequency modulator comprising a blocking oscillator, said oscillator including a semi-conductor device having an emitter, a base and a collector; a pulse transformer having a main winding, a feedback winding and a control winding mounted on a high permeability core, said main winding being connected to said collector; a parallel resistance-capacitance timing network connected between said feedback winding and said base, a source of input intelligence signals, an integrator for integrating said intelligence signals, a semi-conductor chopper having an emitter, a base and a collector; means for connecting said emitter and said collector of said chopper across said integrator, and means for connecting said control winding to said base of said chopper.
